UNITED STATES PATENT OFFICE.

GEORGE FREDERICK COOKE, OF LONDON, ENGLAND, ASSIGNOR TO BRITISH AUTOMOBILE EQUIPMENT COMPANY LIMITED, OF LONDON, ENGLAND.

METHOD AND APPARATUS FOR MANUFACTURING RADIATOR-TUBES.

1,339,104.

Specification of Letters Patent.

Patented May 4, 1920.

Application filed April 9, 1919. Serial No. 288,833.

To all whom it may concern:

Be it known that I, GEORGE FREDERICK COOKE, a subject of the King of Great Britain, residing at 2 Fairfax road, Bedford Park, London, England, have invented a new and useful Method and Apparatus for Manufacturing Radiator-Tubes, of which the following is a specification.

My invention relates to radiators such as are employed in connection with internal combustion motors and to that class of radiator which is built up of a number of tubes each formed by folding a strip of metal along the center of its length the middle portion of such folded strip constituting a tube while the side portions are pressed together and corrugated.

The main object of my invention is to provide a construction of tube of this type in which the shape of the corrugated portion is such that it can be obtained in one operation by drawing or rolling, the invention also comprising a machine whereby this operation can be carried out.

To this end, according to the invention, I provide a machine which comprises a bed-plate or frame carrying at its upper part what I term an anvil, which is preferably arranged at an inclination to the horizontal and along or down which the metal strip to be treated is passed. This anvil is of a shape resembling an upright blade or tongue with its upper end tapering on both sides, so that in cross section the said upper end is of approximately triangular shape with rounded apex. In conjunction with this anvil I provide a roller the periphery of which is grooved to a shape corresponding to that of the taper upper end of the anvil with which the said grooved periphery engages, in such a manner that when the metal strip or sheet to be worked is passed down the anvil between it and the roller, it is folded or bent to a shape corresponding to that of the anvil. The anvil extends beyond the periphery of the roller and guides the folded or bent metal sheet between a pair of oppositely rotating helical rollers which are arranged with their axes parallel and in a horizontal plane, and the helices of which are respectively right and left hand and mesh together.

As the folded metal sheet is fed between the pair of helical rollers, it has imparted to it, at its lower portion the corrugated

shape, the two leaves of the folded metal sheet being pressed together at the lower end and forming a series of corrugations or pockets alternately on either side.

The contacting ends of the metal sheet or strip are secured together either by solder, or by electric welding or in any other suitable way, and the series of tubes thus prepared is built up to form a radiator by assembling the said tubes alternately in opposite directions in the known manner.

To enable the invention to be fully understood I will describe it by reference to the accompanying drawing, in which:

Figure 1 is a central longitudinal section of a machine for the production of corrugated tubes according to the invention, and

Fig. 2 is a sectional end view thereof, the section being taken on the line 2-2, Fig. 1.

Fig. 3 is a sectional plan view, the section being taken on the line 3-3, of Fig. 1.

Fig. 4 is a sectional view drawn to a larger scale illustrating the operation of corrugating.

Fig. 5 is a sectional view of one of the corrugated tubes, and

Fig. 6 is a view similar to Fig. 5 showing four tubes assembled together in the manner to form a radiator.

a indicates the bed-plate or frame of the machine and *b* is the so-called anvil, which is mounted upon the said plate *a* and secured thereto by the screws *b*¹. The said anvil is of the shape indicated in the drawing, that is to say, it comprises a bottom or base with an upright blade *b*², the upper edge of which is inclined to the horizontal and is more or less triangular in cross section with a rounded apex. *c* is the roller which operates with the anvil *b* and *d* is the peripheral groove provided therein, the said groove being of a shape in cross section which corresponds with the taper blade *b*² of the anvil *b* with which it meshes as clearly shown. The roller *c* is keyed upon the shaft *e* which is mounted in bearings *e*¹.

f and *g* are the two helical rollers for effecting the corrugating operation, the axes of which rollers are arranged parallel to one another in a horizontal plane and the helices of which are right and left hand, respectively, and mesh together as clearly shown in Fig. 3. These rollers are mounted in bearings *h* on either end of the bed-plate *a*, which bearings are adjustably mounted

110

thereon so that the distance between the said rollers can be adjusted, as may be required, according to the gage of the metal strip being operated upon.

- 5 The rollers *c*, *f* and *g* are driven from the upright shaft *i* which is furnished with a worm *j* gearing with the worm-wheel *k* keyed upon the roller shaft *e* and with a worm-wheel *l* which gears with a helical 50
10 wheel *m* upon the helical roller *f*, which helical wheel is in mesh with a similar wheel *n* upon the other roller *g*. By the described construction—the upper roller *c* is turned and simultaneously with this movement the 55
15 two rollers *f* and *g* are rotated in opposite directions.

The machine operates as follows, that is to say, the sheet or strip of metal *A* to be corrugated is moved down the inclined anvil *b* 20 so as to pass between the said anvil and the roller *c* which folds it over or curves it to the shape of the upper part *b*² of the said anvil, as shown in Fig. 2. After passing between the roller and anvil the folded 25 sheet comes into engagement with the helical rollers *f* and *g* which impart to it the corrugated shape indicated by the shade lines in Fig. 1, and also seen in cross section in Figs. 5 and 6, the operation by which 30 these corrugations are obtained being illustrated clearly in Fig. 4. As will be understood, the folded metal sheet passes between the helical rollers at an inclination to the axes of the latter, the complete depth from 35 top to bottom of the corrugation not being at once obtained but only gradually as the strip passes between the said rollers.

As above described, the meeting edges of the corrugated tube are secured together in 40 any convenient way and, in practice, solder may be forced through a jet secured to the machine at the inner end of the helical rollers, the solder spreading between the contacting edges of the strip which is heated 45 sufficiently to melt the solder. Any other suitable method of connecting the tube edges may, however be adopted, such as electric welding.

Fig. 6 illustrates the method of forming a

radiator from a series of tubes made in accordance with the invention, and, as will be seen, the tubes are arranged alternately in opposite directions, that is to say, with the narrow end of one in contact with the broad or base end of the adjacent tubes, the result 55 being that a series of tubes with a series of through passages are obtained.

It will be seen that tubes made as above described possess a relatively large cooling surface and offer little resistance to the passage of the air, or other cooling medium, by reason of the fact that the surfaces of the corrugations in the direction of their length are curved.

Claims:

1. In a method of manufacturing radiator tubes from a single sheet or strip of metal, the steps of folding the strip into approximately V-shape to form opposite side portions, then corrugating and placing the longitudinal edges of said side portions together, and maintaining the parts of the side portions adjacent the fold in spaced relation during the corrugating step to provide a longitudinal passage. 75

2. A machine for producing corrugated tubes from sheet metal comprising an anvil and a co-acting grooved roller for folding the metal sheet or strip, in combination with a pair of helical rollers which mesh together, the axes of which are parallel and the helices of which are right and left hand, respectively, for corrugating the folded metal strip, and means for rotating the grooved roller and the corrugating rollers, substantially as hereinbefore described. 80

3. In a method of manufacturing radiator tubes from a single sheet or strip of metal, the steps of folding the strip into approximately V-shape to form opposite side portions, then applying pressure dies to the edge portions of said side portions to force the longitudinal edges together and corrugate them transversely, and maintaining the parts of the side portions adjacent the fold 90 in spaced relation during the corrugating step to provide a longitudinal passage. 95

GEORGE FREDERICK COOKE.
